UNITED STATES PATENT OFFICE.

LOUIS G. LAUREAU, OF PHILADELPHIA, PENNSYLVANIA.

PIT-FURNACE.

SPECIFICATION forming part of Letters Patent No. 411,814, dated October 1, 1889.

Application filed April 22, 1889. Serial No. 308,136. (No model.)

To all whom it may concern:

Be it known that I, LOUIS G. LAUREAU, of Philadelphia, Philadelphia county, Pennsylvania, have invented certain new and useful

5 Improvements in Pit-Furnaces, of which the following is a specification.

This invention pertains to that class of pit-furnaces designed for the "soaking" of newly-cast ingots. A newly-cast ingot begins to cool at its outside, and the cooling gradually reaches the center. The center being the last to cool, the shrinkages are of course at the center. A partially-cooled ingot may contain a total heat corresponding with the total heat required in an ingot fit to be rolled; but the heat may be so low at the outside of the ingot that it is not fit for rolling, while the central portions of the ingot are hotter than is necessary. What is wanted is an equalization of the heat in cooling, so that the total heat in the partially-cooled ingot may be available for the rolling process. If the freshly-cast ingot be placed in a pit alongside a partially-cooled ingot, the freshly-cast ingot will part with heat, and at the same time the center of the partly-cooled ingot will part with heat, and both these items of heat will serve to elevate the temperature of the outer portions of the partly-cooled ingot, whereby there is established a tendency toward equalization in the partly-cooled ingot. Otherwise stated, the ingots are cooled in a heated atmosphere, whereby the cooling is rendered substantially uniform throughout the body of the ingot, the heated atmosphere being maintained by the heat dispensed by the ingots in cooling. Sufficient heat should be added to compensate for the heat which would be dispensed by the ingots during the equalizing process of cooling.

40 My improvements relate to the construction of pit-furnaces in which ingots are to be placed for the purpose of equalizing their heat during the process of solidification or further cooling.

45 My improvements will be readily understood from the following description, taken in connection with the accompanying drawings, in which—

50 Figure 1 is a side elevation, part in vertical section, of a pit-furnace constructed in accord-

ance with my invention; and Fig. 2, a plan of the same, half in horizontal section.

In the drawings, A indicates the furnace of general rectangular plan and having a depth 55 at least equal to the length of ingots to be treated; B, the bed of the furnace sloped from the ends toward the center; C, the roof of the furnace, provided with openings and covers therefor, by which the ingots may be 60 placed in the furnace by being let down endwise therein; D, the regenerator structures at each end of the furnace; E, the gas portion of the regenerators to serve in the usual manner to heat the incoming gases; F, the air portion of the regenerators to serve in a similar manner in heating the incoming air of combustion; G, combustion-nozzles reaching from the regenerator structures to the ends of the furnace; H, a slag-pit or tunnel crossing under 70 the center of the furnace; J, a wall disposed longitudinally in the furnace and extending vertically from the floor to the roof-cover thereof; K, arches springing from the side walls of the furnace and from the central wall, and serving to support the roof of the furnace; L, a port through the wall J at the center of its base; M, a port in the floor of the furnace, communicating with the slag-tunnel; N, the furnace-chamber upon one 80 side of the wall J, and O the furnace-chamber upon the other side of that wall.

The regenerators are to be arranged to work as usual, so that gas passing through one of the gas-regenerators and air passing through 85 its fellow air-regenerator become heated and join and go into combustion at the appropriate nozzle leading to the furnace, the hot products of combustion after passing through the furnace passing through and heating the 90 gas-regenerator and air-regenerator at the other end of the furnace, and escaping thence to the chimney, the action of the regenerators being reversed when the one pair has become cooled and the other pair properly heated. 95 The combustion of the gases within the furnace yields heat to the ingots therein and to the furnace-walls, which radiate to the atmosphere a portion of the heat received and to the division-wall J, which wall does not 100 radiate its heat to the atmosphere, but serves as a regenerator and equalizer of heat for the

ingots. The division-wall J also serves to support the roofing of the furnace, and permits of the furnace being built very much wider than would otherwise be possible, thus rendering possible an increase in the bed-area and capacity of the furnace. The wall also serves in supporting the ingots. The ingots are set upright in the furnace in numbers, and in case one ingot tumbles all of its fellows are liable to be knocked down, causing danger, annoyance, delay, and waste. The wall J serves in supporting the ingots sidewise, and serves also as a guide to the attendant in reaching down after his ingots with his tongs and in placing the ingots. The slag works down the bed of the furnace toward the center and finds its way to the slag-tunnel through port M, the two chambers being in communication at the floor-level through port L.

20 The roof of the furnace proper, it will be noticed, is entirely open, except at the arches K. The edges of the covers join over these arches, and the removal of a cover opens a

port leading into the furnace, and bounded at the ends by the division-wall and a side 25 wall of the furnace and at the sides by the sides of its contiguous arch-walls.

I claim as my invention—

In a pit-furnace, the combination, substantially as set forth, of a furnace substantially 30 rectangular in plan, a regenerator structure at each end of the furnace, combustion-nozzles leading from the regenerator structures to the furnace, a longitudinal wall disposed centrally in the furnace and extending from 35 the floor to the roof thereof, and a series of arch-walls arranged in the chambers at each side of said longitudinal wall at right angles to said wall, and springing therefrom and from the side walls of the furnace and extending to the roof of the furnace.

LOUIS G. LAUREAU.
